UNITED STATES PATENT OFFICE.

NATHAN WILKINSON, OF MILWAUKEE, WISCONSIN, ASSIGNOR, BY MESNE ASSIGNMENTS, TO ALLIS-CHALMERS MANUFACTURING COMPANY, A CORPORATION OF DELAWARE.

TIME-ELEMENT DEVICE.

1,118,608.

Specification of Letters Patent. Patented Nov. 24, 1914.

Application filed April 17, 1911. Serial No. 821,665.

To all whom it may concern:

Be it known that I, NATHAN WILKINSON, a citizen of the United States, residing at Milwaukee, in the county of Milwaukee and 5 State of Wisconsin, have invented certain new and useful Improvements in Time-Element Devices, of which the following is a full, clear, and exact specification.

My invention relates to thermostats, particularly in connection with time-element circuit-breaking devices.

In the ordinary construction of thermostats, the two elements, formed of different metals, have usually been riveted together, 15 one end of the composite strip being fixed while the other is free to move to accomplish the desired result. This produces a very flimsy structure, the composite strip being easily bent. Moreover, the deflection 20 of such a composite strip is caused merely by the differential expansion of the strips upon equal heating. When thermostats have been used in connection with electric switches, the thermostat operating or forming the movable element of the switch, the 25 operation of such switch has been exceedingly slow, thus making arcing at the contacts of the switch practically inevitable.

It is the object of my present invention 30 to avoid these difficulties. This is accomplished by making the thermostat in a truss form, the two strips of the thermostat and their common base preferably forming a triangle. The resultant structure is firm 35 and substantial, is of easy and permanent adjustment, and is not easily damaged. Moreover, it allows the heating of one of the elements of the thermostat without the other, as by an electric heating coil wrapped 40 upon one strip of the thermostat only; thus the deflection is not dependent upon different co-efficients of expansion of the materials forming the two strips, which may be made of the same material. This thermo- 45 stat is combined with mechanism for obtaining a snap action of a switch operated by the thermostat.

The various novel features of my invention will appear from the description and 50 drawings, and will be particularly pointed out in the claims.

Figure 1 shows a thermostat embodying 55 my invention, as applied to an overload and no-voltage circuit-breaker, the switch actuated by the thermostat being in closed po-

sition; and, Fig. 2 shows the same thermostat just after it has tripped its switch.

The thermostat proper consists of two metal strips or rods 10 and 11. The strip 10 is preferably made of a brass tube with 60 the ends flattened, while the strip 11 is made of a flat steel spring. However, the strips may be made of any desired material, and are not necessarily of unlike material. The left hand ends of the strips 10 and 11 are mounted in common on a post 12, being spaced apart by a thick washer 13 and held in place by a screw 14. Their right hand ends are fastened firmly together in any desired manner, as by rivets or solder, or by a screw 65 15, the latter also serving as an adjusting screw which may be locked in position by a hook 16 formed by an extension of the spring strip 11. The strip or tube 10 is wound with a heating coil 17, one end of 70 which is connected to a contact terminal 18 and the other, by way of a shunt 20, to the movable spring contact 19 of a switch. The movable contact 19 is mounted on a bell-crank lever 21, and co-operates with a fixed 75 contact 22 at the bottom of a contact terminal 23, the two contact terminals 18 and 23 being normally bridged by a member 24 which may be lifted out of engagement with 80 one or both by an overload coil 25. The 85 bridging member 24 thus short-circuits the heating coil 17 and the switch 19. Pivoted to the lower end of the vertical arm of the bell-crank lever 21 is a second bell-crank lever 26, the long horizontal arm of which 90 extends above and substantially parallel to the strip 11 and may be engaged near its fulcrum by the adjusting screw 15. The bell-crank levers 21 and 26 are biased in clockwise and counter-clockwise directions 95 respectively by a spring 27, but are normally held from movement in such directions by the weight of the bridging member 24 resting on the screw 28 carried by the horizontal arm of the bell-crank lever 21, and by a stop 29 with which a notch at the 100 end of the horizontal arm of the bell-crank lever 26 engages.

The thermostat and switch above described are shown as controlling a circuit-breaker 30, 105 arranged in the mains 31 of an electrical distribution system of any desired type. The circuit-breaker is biased to open position, but may be held closed by the no-voltage coil 32, the circuit of which includes the contact ter- 110

minals 18 and 23 and some connection between them. This connection is normally the bridging member 24, the parts being as shown in Fig. 1. Upon an overload, however, the overload magnet 25 lifts the bridging member 24, thus compelling the current for the circuit of the no-voltage coil 32 to pass through the heating coil 17 and the switch contacts 19 and 22. The coil 17 immediately begins to heat the strip or tube 10, causing it to expand longitudinally and raise the right hand or joined ends of the strips 10 and 11. The coil 17 has little or no heating effect on the strip 11. If the over-load is but momentary, the overload coil 25 allows the bridging member 24 to drop to short-circuit the heating coil 17 and the switch contacts 19 and 22. If the overload continues, however, the expansion of the tube 10 under the influence of the heating coil 17 continues until the screw 15 has lifted the left hand end of the horizontal arm of the bell-crank lever 26 clear of the stop 29, whereupon the spring 27 immediately contracts and moves the parts 26, 21, and 19 to the left, to the position shown in Fig. 2. This separates the switch contacts 19 and 22, thus breaking the circuit of the no-voltage coil 32 and tripping the circuit-breaker 30. Upon the opening of the circuit-breaker 30 and the consequent deenergization of the overload magnet 25, the bridging member 24 drops and forces the screw 28 downward, thus moving the contact 19 again into engagement with the contact 22, and the bell-crank lever 26 at least far enough to the right to allow the notch at its end to engage the stop 29. Since it takes some little time for the strip 10 to cool and contract to its former length, such notch does not immediately engage the stop 29. Thus if the circuit-breaker 30 is immediately re-closed it will immediately be re-tripped if the overload still continues, for the lifting of the bridging member 24 by the magnet 25 allows the immediate separation of the contacts 19 and 22 and the immediate interruption of the circuit of the no-voltage magnet 32. However, if the circuit-breaker is not immediately re-closed, or if it is re-closed but the overload has ceased, the bridging member 24 will remain down, and hold the contacts 19 and 22 in engagement until by the cooling and contraction of the strip 10 the notch in the end of the bell-crank lever 26 has again engaged the stop 29. If an overload then occurs, the circuit-breaker 30

will be tripped only after an interval of time, in the manner above described. This interval of time may be adjusted with great accuracy by the screw 15.

The thermostat above described, whether with or without the heating coil 17 and the switch contacts 19 and 22, may be used for any purpose for which any thermostat may be used. Its construction, as well as that of the parts associated with it, may be modified widely, and in the following claims I aim to cover all such modifications which come within the spirit and scope of my invention as defined in the following claims.

What I claim as new is:

1. A thermostat, comprising two members fixed and spaced apart at one end and joined together at the other end, and an adjustable part extending through said members at their joined ends, a portion of one of said members being resilient and engaging said adjustable part to form a lock therefor.

2. In combination, a support, a thermostatic element mounted on said support, a switch, a resilient member attached to said support for biasing said switch to one position, and latching means for holding said switch in another position, said thermostat being normally free from and adapted to engage and trip said latch.

3. In combination, a switch biased to one position, a latch for holding said switch in another position, a thermostat comprising two members spaced apart at one end and secured together at the other end, and an adjustable element at the latter end for tripping said latch.

4. In combination, a switch, means for biasing said switch to one position, a latch for holding said switch in another position, said switch-biasing means biasing said latch to switch holding position, and a thermostat for tripping said latch.

5. In combination, a switch, a latch for holding said switch in one position, means for biasing said switch to another position, said switch biasing means being effective to bias said latch toward one position, and a thermostat for tripping said latch.

In testimony whereof I affix my signature, in the presence of two witnesses.

NATHAN WILKINSON.
